UNITED STATES PATENT OFFICE.

HARRY J. TROXELL, OF GETTYSBURG, PENNSYLVANIA.

CHANGEABLE EXHIBITOR FOR CARDS, PICTURES, SIGNS, AND THE LIKE.

1,254,746.

Specification of Letters Patent. Patented Jan. 29, 1918.

Application filed August 20, 1917. Serial No. 187,179.

To all whom it may concern:

Be it known that I, HARRY J. TROXELL, a citizen of the United States, residing at Gettysburg, in the county of Adams and State of Pennsylvania, have invented a certain new and useful Improvement in Changeable Exhibitors for Cards, Pictures, Signs, and the like, of which the following is a full, clear, and exact description.

An object of this invention is to provide a changeable exhibitor primarily designed for use in connection with show-window displays and the like, and for advertising purposes, or in any other capacity where a device of this character would be useful.

A further object is to provide such a device which is simple in construction and operation, compact and self-contained, adapted to be easily transported and installed for operation, inexpensive to manufacture, and capable of continuous operation without attention.

The invention consists in a changeable exhibitor having a projecting apparatus provided with an intermittently rotating carrier in which are placed, as desired, a number of slides containing advertising cards or pictures or signs, or other matter to be exhibited, and means for supplying power to impart motion to the carrier and its associated parts; and the invention also consists in various details of construction and operation, as I will proceed now to explain and finally claim.

In the accompanying drawings illustrating the invention, in the several figures of which like parts are similarly designated, Figure 1 is a partial central vertical section of the complete apparatus. Fig. 2 is a partial transverse section showing the projecting apparatus in front elevation. Fig. 3 is a side view of the cam disk showing the cam for operating the slide carrier. Fig. 4 is a reverse side view of the cam disk showing the cam for operating the shutter. Fig. 5 is a partial section of the slide carrier. Fig. 6 is a view of a slide such as may be used with the machine.

The projecting apparatus is arranged in a suitable light-proof casing having a bottom 1, top 2, sides 3 and 4 and back 5, and this casing is provided at its front end with a screen 6 of any suitable type, such as a Rembusch transparent glass screen, mounted in a suitable frame 7. The top 2 is preferably hinged, as shown in Fig. 2, to admit of

ready access to the interior of the casing and the operating parts.

The back 5 is provided with a suitable support 8 for a source of artificial light 9, such as an incandescent electric lamp 9, but it is obvious that other light may be used. This light is provided with a reflector or concentrator 10, and the whole is inclosed in a casing 11 hinged to the back 5, as at 12, 85 or otherwise suitably retained in position.

The reflector or concentrator 10 directs the light of the lamp 9 to the condenser lens 13, disposed in proper relation thereto.

Mounted on a shaft 14 suitably supported in bearing brackets 15 and 16 secured to the bottom 1 is a slide carrier or disk 17, provided with pockets or slots 18 to receive slides 19, such as shown in Fig. 6, containing advertising matter, views, or the like, openings 20 being made in the disk to conform to the shape of the slides 19 and the screen 6. The slides are held in the pockets 18 by cotter pins 21 or other suitable devices. The axis or shaft 14 of disk 17 is so located with respect to the lens 13 that the slides will be brought into focus therewith.

Also mounted on the shaft 14 is a wheel 22 provided with pins 23 in number corresponding to the number of slides provided for in the disk 17, and these pins engage successively with a cam slot 24 in a disk 25 mounted on a shaft 26 at right angles to the shaft 14 and supported in suitable bearing brackets 27. Other suitable mechanism for imparting intermittent motion to the disk 17 may, of course, be substituted if desired. The shaft 26 and cam disk 25 are shown as driven by pulleys 28, 29, 30, 31, 32, 33, 34 and 35 and suitable belts, from a motor or other source of power 36, but other suitable power transmission may be used if desired, such as a train of gears. The transmission mechanism preferably is such as to reduce the speed of the motor as applied to the exhibiting agents.

Mounted in suitable guides 37 in front of the lens 13 is a shutter 38 provided with an extension 39 which cooperates with a lever 40 mounted in a bearing 41 and operated by a cam face 42 on the disk 25 by which the shutter is raised and lowered at proper intervals as the carrier and cam disk revolve.

A projecting lens 43 is adjustably supported upon a rod 44 secured to a bracket 45 adjustably mounted upon the bracket 15, and this lens may be moved along the rod

44 or said rod may be moved in its bracket 45 and secured in adjusted position by set screws 46 and 47, respectively, as shown, to enlarge or diminish the image thrown upon 5 the screen.

The operation of the device is as follows:—The pockets 18 of the disk 17 are filled with slides containing advertising matter, views, etc., and the devices 21 inserted to prevent the slides from falling out as the disk revolves. The lamp 9 is then lighted and the motor 36 or other source of power is started and the cam disk 25 caused to rotate thereby through the transmission 10 mechanism. As the disk 25 rotates in the direction indicated by the arrow, one of the pins 23 of wheel 22 will follow the cam groove 24 until it runs out at the end 48 of the groove. At the same time that this pin 15 is leaving the groove 24 the next pin will be entering it at 49, thereby rotating shaft 14 and with it disk 17 to move a new slide to position between the lenses 13 and 43. But before the pin 23 leaves groove 24, cam 42 20 operates on lever 40 to move shutter 38 into position over the opening 50 of the lens 13, thus cutting off the light, and the shutter is held in this position by the cam 42 and lever 40 until disk 17 has rotated to bring a 25 new slide into position. Then the shutter drops down and the image of the view or advertising matter is projected upon screen 6. If desired, a spring or other device may be applied to the lever 40 or to the shutter 38 to supplement gravity in the descent of the shutter.

This operation may be continued without the attention of an operator, until it is desired to substitute a new set of slides for 40 those then in the disk or the power cut off.

If desired, the rotation of disk 17 may be made so slow as to allow of a change of slides without interfering with the operation of the machine.

45 Various changes in details of construction and arrangement of parts are permissible within the spirit of the invention and the scope of the claims following.

What I claim is:—

50 1. In a changeable exhibitor, a casing provided with a screen at one end thereof, a projecting apparatus at the other end thereof, a rotatable disk provided with a plurality of slides interposed in said projecting apparatus, a pin-wheel mounted to turn with

said disk, and a grooved cam co-operating with said pin-wheel for imparting intermittent rotary motion thereto and to said disk.

2. In a changeable exhibitor, a light-proof casing provided with a screen, a condensing lens, a projecting lens, a rotatable slide-carrier interposed between said lenses, a source of light for said lenses whereby the views on said slides are projected upon the screen, a constantly actuated grooved cam coaxing 60 with a pin-wheel for imparting intermittent rotation to said slide carrier, and a shutter operable during the rotation of said slide carrier for obstructing the passage of light.

3. In a changeable exhibitor, a screen, a 70 projecting apparatus, a rotatable slide carrying disk interposed in said projecting apparatus, a cam and pin-wheel mechanism for imparting intermittent rotary motion to said disk, constantly actuated transmission 75 mechanism connected with said cam for imparting constant rotary motion thereto, a source of light for said projecting apparatus, a shutter slidably mounted between said source of light and said disk, and means operated by said cam for interposing said shutter between said light and disk when said disk rotates.

4. In a changeable exhibitor, a projecting apparatus comprising a stationary condensing lens, an adjustable projecting lens and an intermittently-rotated slide-carrying disk interposed between said lenses, a number of slide holders arranged radially of said disk and adapted by rotation to be brought into focus between said lenses, a shaft on which said disk is mounted, a pin-wheel on said shaft having pins of a number to correspond with the number of slides of said disk, a cam adapted to engage said pins to impart 90 step-by-step rotation to said disk whereby at each step a slide is brought into focus between said lenses, a shutter mounted to slide between said condensing lens and disk during the rotation of the disk, a cam and 95 lever mechanism so timed as to impart motion to said shutter in proper relation to the rotation of said disk, and means for supplying power to said moving parts.

In testimony whereof I have hereunto set 105 my hand this 17th day of August A. D. 1917.

HARRY J. TROXELL.
